ELECTRICAL CONNECTER

Filed Oct. 28, 1935.

UNITED STATES PATENT OFFICE

2,142,818

ELECTRICAL CONNECTER

Gunnard W. Jacobson, Chicago, Ill., assignor to
Illinois Tool Works, Chicago, Ill., a corporation
of Illinois

Application October 28, 1935, Serial No. 47,027

5 Claims. (Cl. 173—269)

This invention relates generally to electrical connectors or terminals and to methods of making same, and more particularly to electrical terminals formed from sheet metal.

5 It has heretofore been the practice in the manufacture of electrical terminals requiring a button or head at their outer extremities, to produce such parts from solid round stock as distinguished from flat or sheet stock. It is one of 10 the important objects of my invention to materially reduce the cost of manufacturing such type of electrical terminals and to this end I propose to manufacture them from flat sheets of conductive material.

15 More specifically, the invention contemplates a simple and practical method of producing electrical terminals having enlarged or head extremities by forming a blank from conductive sheet material and then shaping this blank to the desired form.

20 Still more specifically, the invention contemplates an electrical connector or terminal in which the head at the free extremity thereof is presented by a cup shaped section of thin conductive material as distinguished from solid head structures heretofore employed.

The foregoing and numerous other objects will be more apparent from the following detailed description when considered in connection with 30 the accompanying drawing wherein:

Figure 1 is a side elevational view of an electrical connector or terminal which is representative of one embodiment of my invention, the same being disclosed in operative association with 35 an electrical conductor or wire;

Figure 2 is a plan view of the device as shown in Figure 1;

Figure 3 is a central longitudinal sectional view of the device taken substantially along the line 40 3—3 of Figure 2;

Figure 4 is a perspective view of the electrical connector or terminal prior to its operative association with an electrical conductor;

Figure 5 is an end elevational view as viewed 45 from the right of Figure 4;

Figure 6 is a transverse sectional view taken substantially along the line 6—6 of Figure 1;

Figure 7 is a transverse sectional view taken substantially along the line 7—7 of Figure 1; and

50 Figure 8 discloses the blank from which the electrical connector or terminal of the present invention may be formed.

Referring now to the drawing wherein like numerals have been employed to designate similar parts throughout the various views, it will be

seen that my invention contemplates an electrical connector or terminal as indicated generally by the numeral 10. The invention also contemplates novel methods whereby the connector 10 may be produced from sheet or thin conductive material. 5 One method contemplated by the present invention whereby my improved electrical terminal may be produced includes the step of forming from a sheet of flat stock a blank 10a as shown in Figure 8. This blank presents three connected sections indicated generally by the letter A, the letter B, and the letter C.

In forming or shaping the electrical terminal 10 from the blank 10a, the sections A and B are bent into U-shaped form, the larger section A 15 serving to receive the insulated portion 12 of a flexible conductor 14 and the smaller section B serving to receive the electrical conductor proper 16 as clearly illustrated in Figures 1 to 3 inclusive. 20

The section C, which is connected to the section B through the agency of a neck portion 18, is cupped so as to present a head or button 20, the diameter of the head or button 20 being larger than the section B, and the section B being 25 positioned substantially co-axial with said head.

When the electrical connector or terminal is to be applied to the flexible conductor 14, it is only necessary to place the conductor proper 16 within the section B and the insulated portion 30 12 within the section A as clearly shown in Figure 3 and then bend the free extremities of the sections toward each other so as to produce cylindrical conductor gripping parts. To secure these free extremities of the U-shaped sections A and 35 B against relative axial movement when clamped against the flexible conductor, I provide each of the sections with complementary tongue and groove configurations, the tongue 22 on one free extremity of the section A coacting with a companion V-shaped recess 24 provided in the other free extremity of the section A, and a tongue 26 on the section B coacting similarly with a recess 28. In this manner the bent together portions of the sections A and B are positively secured 40 45 against relative axial displacement. If it is desired, the tongues 22 and 26 may be urged slightly inwardly to more effectively establish frictional contact or connection with the flexible conductor.

The hollow semi-spherical or cup-shaped head 50 55 20 functions equally as well as a solid head or button in establishing electrical contact. It is not necessary for a clear understanding of the present invention to disclose or describe the electrical socket or terminal receiving device with 55

which my improved electrical connector may be used. It is sufficient to state that the simplified sheet metal device contemplated by the present invention is equally as efficient when in use as solid electrical terminals which have heretofore been employed. Furthermore, the ease with which my improved electrical terminal may be made by punches and dies from a small piece of flat stock greatly reduces the cost of manufacture. While I have disclosed one specific embodiment of the invention, it will be apparent that other modifications and changes may be made without departing from the spirit and scope of the appended claims.

Having thus described my invention, what I claim as new and desire to secure by Letters Patent is:

1. An electrical terminal comprising a member bent to form an intermediate portion adapted to receive a wire, an end portion adapted to receive insulation about the wire and a dome-shaped contact portion at the opposite end, said contact portion being arranged substantially coaxially with respect to said wire engaging portion and being formed of sheet metal so that the face opposite said dome-shaped configuration is concave, the contact having the concave face presented toward the said intermediate portion, said intermediate and end portions being bendable about the wire and insulation to clamp the same therein, and an integrally formed, relatively narrow strip of sheet metal extending from an edge of the said intermediate portion to a point adjacent the periphery of the contact portion whereby to provide an integral, unitary member readily capable of being cut and formed from sheet metal.

2. An electrical terminal comprising a sheet metal member bent to form an intermediate portion adapted to receive a wire and to extend substantially axially of the wire, an end portion adapted to receive insulation about the wire and a contact portion at the opposite end comprising a sheet metal member distorted outwardly to form a substantially hemispherical contact member, one face of said sheet contact member being concave, said hemispherical contact member being substantially co-axial with the longitudinal axes of said intermediate portion and said end portion and having the concave face thereof presented toward the said end portion, said intermediate portion and end portion being bendable about the wire and insulation to clamp the same therein, and an integrally formed, relatively narrow strip of sheet metal extending from an edge of the said intermediate portion to a point adjacent the periphery of the contact member whereby to provide an integral, unitary electrical terminal member readily capable of being cut and formed from sheet metal.

3. An electrical terminal comprising a sheet metal member bent to form a substantially U-

shaped intermediate portion adapted to receive a wire, and a substantially U-shaped end portion adapted to receive insulation about the wire and a contact at the opposite end of said member, said contact being formed outwardly to provide a convex, dome-shaped configuration, the contact being of sheet metal with one face thereof convex, said dome-shaped contact being arranged substantially co-axially of the longitudinal axis of said U-shaped portions and with the concave face presented toward the U-shaped portions and the arms of said U-shaped portions being bendable about the wire and insulation to clamp the same therein.

4. An electrical terminal comprising a one-piece sheet metal member bent to form a substantially U-shaped intermediate portion adapted to receive a wire, a substantially U-shaped end portion adapted to receive insulation about a wire, one leg of each of said U-shaped portions having a projection and the other leg of each U-shaped portion having a complementary recess to receive said projection, and a contact at the opposite end of said member, said contact being formed outwardly to provide a convex configuration, the contact being of sheet metal and having the interior face thereof of concave configuration, said contact being mounted substantially co-axially of the longitudinal axes of said U-shaped portions and being arranged with its convex face presented away from said U-shaped portions, the arms of said U-shaped portions being bendable about the wire and insulation to clamp the same therein and said projections engaging in said complementary recesses to interlock the arms of said U-shaped portions against relative axial movement.

5. An electrical terminal formed of an integral piece of sheet metal having a longitudinally extending portion bent so as to engage about the end of a wire, and a dome-shaped contact member at one end of said longitudinally extending wire-engaging portion, said contact member comprising a sheet metal piece distorted outwardly to provide a substantially dome-like convex contact face, the opposite face of said sheet member being concave, said dome-shaped contact member being arranged substantially coaxially of the longitudinal axis of said longitudinally extending wire-engaging portion and having its concave face presented toward said longitudinally extending member, the longitudinally extending portion being bendable about the wire to clamp the same thereon, and an integrally formed, relatively narrow strip of sheet metal extending from an edge of the said longitudinally extending portion to a point adjacent the periphery of the contact member whereby to provide an integral unitary terminal member capable of being readily cut and formed from sheet metal.

GUNNARD W. JACOBSON.
